UNITED STATES PATENT OFFICE.

WALDO C. BRYANT, OF BRIDGEPORT, CONNECTICUT, ASSIGNOR TO THE BRYANT ELECTRIC COMPANY, OF SAME PLACE.

CONTACT FOR INCANDESCENT-LAMP BASES, &c.

SPECIFICATION forming part of Letters Patent No. 651,695, dated June 12, 1900.

Application filed December 13, 1898. Serial No. 699,150. (No model.)

To all whom it may concern:

Be it known that I, WALDO C. BRYANT, a citizen of the United States of America, residing in Bridgeport, Fairfield county, State 5 of Connecticut, have invented an Improved Contact for Incandescent-Lamp Bases, &c., of which the following is a specification.

The object of my invention is to make a simple and efficient contact for incandescent-lamp bases, plugs, receptacles, &c., more 10 particularly of the Edison type and of that class in which porcelain or like insulating buttons or bodies are employed instead of plaster.

15. In the accompanying drawings, Figure 1 is a sectional view of my improved contact-piece and the porcelain button or body before the two are united. Fig. 2 is a sectional view of a lamp base or plug provided with my invention, and Fig. 3 is a sectional view of a socket or receptacle to illustrate the application of my invention thereto.

In Figs. 2 and 3 I have shown my invention as applied to a lamp base and receptacle 25 of the Edison type, A being the screw-shell, of brass, which forms one of the terminals, and B being the bottom contact, which forms the other terminal. My invention has more particular reference to the construction of 30 this bottom contact. Heretofore it has been made of two pieces of brass riveted together.

For the sake of simplicity and economy and to give a uniform and more efficient con-

tact-surface I make the contact-piece of a single piece of sheet metal comprising a tubular portion *b*, considerably longer than the opening in the insulating-button through which it passes, an outwardly-projecting flange *b*², and a rearwardly-projecting flange *b*³, all of one piece of sheet metal. The tubular portion *b* is passed through the eye *d* of the porcelain or other button or body *D*, Fig. 1, and has its small end flanged over into a recess *d*¹ in the porcelain. The rearwardly-projecting flange *b*³ of the enlarged head at 45 the other end of the tube bears against the opposite face of the porcelain.

I claim as my invention—

In an incandescent-lamp base, socket, &c., the combination of an insulating-body having 50 an opening, with a contact, consisting of a tubular portion passing through said opening and secured thereto by flanging one end of the tube, and an outwardly-projecting flange *b*² at the other end, with a rearwardly-projecting flange *b*³ to bear against the insulating-body, the flanges being in one with the tube, substantially as described.

In testimony whereof I have signed my name to this specification in the presence of 60 two subscribing witnesses.

WALDO C. BRYANT.
